TYPEWRITING MACHINE

William A. Dobson, Wethersfield, Conn., assignor
to Underwood Elliott Fisher Company, New
York, N. Y., a corporation of Delaware

Application November 23, 1938, Serial No. 242,013

8 Claims. (Cl. 197—114)

This invention relates to line-space and detent-release devices for controlling the rotation of a typewriter platen.

The general objects of this invention are to provide a simple and rugged line-space device particularly adapted for economic manufacture; and to provide a simple device operable to effect both line-spacing and platen detent release in a convenient manner, to be actuatable by a momentary finger touch by the typist to accomplish either function.

A further object is to provide a device of this character having a manually actuatable member normally operable to rotate the platen in line spacing and adapted to function also, by a simple manipulation, to effect release of the platen detent from cooperative engagement with the platen ratchet wheel, the actuating member, set in detent release position, being readily operated by a flip of the finger to restore the detent to cooperation with the ratchet wheel, whence the member may instantly return to its initial line-spacing position in readiness for that function.

Other objects and advantages will hereinafter appear.

In the drawing,

Figure 1 is a fragmentary perspective view of a typewriter platen carriage assembly partly broken away to facilitate illustration.

Figure 2 is a fragmentary front elevational view of the device as shown in Figure 1.

Figure 3 is a transverse sectional view taken on the line 3—3 of Figure 2, showing the line-space and detent release lever in initial position for line spacing.

Figure 4 is a view similar to Figure 3 but showing the lever in full actuated position at the completion of a line-space stroke, and

Figure 5 is a view similar to Figure 3 but showing the lever in detent-releasing position.

The numeral 6 indicates the usual cylindrical platen carried on a shaft 7, the latter being journaled for rotation in carriage end plates 8, one of which is shown. The platen shaft 7 extends through the end plate 8 and has secured thereon a knob 9 for convenient rotation of the platen in feeding paper into the machine. The hub of the knob 9 abuts the outer face of the end plate 8, a collar 10 on the shaft 7 being arranged to abut the inner face of the end plate 8. The platen 6 has the usual ratchet wheel 11 mounted for rotation therewith, the teeth of the ratchet wheel having a pitch equivalent to one or more line spaces, or increments thereof.

55 A spring detent 12 is secured to a flange 13 of

the carriage end plate 8 by a bolt 14, the free end of this detent being rounded to form a roll 15 pressed into cooperative engagement with a tooth of the ratchet wheel 11. The detent 12 thereby serves to yieldably arrest rotation of the platen to 5 accurately position same for each line-spacing.

A line-space and detent-release lever 16 is mounted for oscillatory and endwise movement on the platen shaft 7, the lever 16 having an elongate aperture 17 engaging the platen shaft. As 10 shown more clearly in Figure 2, the lever 16 is disposed adjacent the ratchet wheel 11 and is guided sidewise by a face of the ratchet wheel on one side, and by the end of collar 10 at the other side. The lever 16 extends upwardly in an arm 18, the free end of which carries a finger-piece 19 integral with the arm and disposed for convenient access by the typist.

The lever 16 carries a dog 20 preferably formed by bending an integral portion of the arm 18 laterally to overlie the ratchet wheel 11. A spring 21 is arranged to yieldably hold the lever 16 in normally ineffective or quiescent position shown in Figure 3, the ends of the spring being attached to a lug 22 on lever 16 and a lug 23 on 20 the end plate 8. Lever 16 is extended downwardly in an arm 24 including a forwardly projecting finger 25 adapted to engage a stop 26 on the end plate 8 when lever 16 is oscillated to rotate the platen in line-spacing. It is to be noted that, with lever 16 in its quiescent position as shown in Figure 3, the lug 22 is in a direct radial line from the platen shaft 7 projecting through the lug 23. In this position the spring 21 is under a slight initial tension, thus holding lever 16 25 in its uppermost position defined by the engagement of the lower end of slot 17 with the platen shaft. The tension of spring 21 yieldably holds the lever 16 against oscillatory movement in its quiescent position, in which position the dog 20 30 is disposed just forwardly of the ratchet tooth 11a or just above the space in front of said tooth.

Line space rotation of the platen is effected by a simple manipulation of lever 16 produced by manually engaging the finger-piece 19 and pressing same downwardly and rearwardly or tangential to the platen axis, that is, generally opposite the direction in which the finger-piece faces, this movement causing the dog 20 to first move into the space forward of the ratchet tooth 11a and 45 thereafter engage the said ratchet tooth. It may be here noted that the manual effort in manipulating lever 16 in its line spacing initial movement is so directed as to overcome the force of spring 21, and the spring is so arranged as to require the 50 55

movement of the lever in such direction that the dog 20 is moved directly into the tooth space ahead of tooth 11a. As dog 20 arrives within the tooth space, the upper end of slot 17 engages the 5 platen shaft 7 and prevents further downward movement of lever 16 so that further force applied to the finger-piece 19 in a generally tangential direction is resolved into a rotative or oscillatory movement of the lever 16 which causes a 10 corresponding rotation of the platen, in that the dog 20 is engaged with the tooth 11a. The oscillatory movement of lever 16 is limited by the engagement of the finger-piece 25 with the stop 26, the angular distance between these elements, 15 with the lever 16 in quiescent position, representing slightly more than the usual line space, that is, the spacing between the end of finger 25 and stop 26 is such as to permit oscillation of lever 16 from its Figure 3 position to that shown in Figure 4. It will be observed that during line space 20 rotation of the platen the end 15 of the detent 12 snaps into the succeeding tooth of the ratchet wheel to yieldably detent the platen in the new line-space position.

25 Lever 16 may also be operated to effect the release of the detent 12 from cooperative engagement with the ratchet wheel 11, the end of arm 24 of lever 16 being arranged to engage roll 15 of the detent 12 and push same to ineffective position as shown in Figure 5, the end of arm 24 having a recess 27 into which the roll 15 seats in its released position. As previously described, lever 16 is pressed rearwardly and downwardly to effect line-space rotation of the platen. 30 When release of the platen detent 12 is desired, the lever 16, that is, the finger-piece 19 thereof, is swung forwardly about the shaft 7 until a tip 28 of arm 24 comes into engagement with the roll 15 and cams same outwardly beyond operative engagement with the ratchet wheel 11. 35 With the roll 15 snapped into the recess 27, lever 16 is held in its detent-released position as shown in Figure 5. When it is desired to restore the detent to normal cooperation with the ratchet wheel 11, a slight rearward flip of the finger-piece 19 is effective to free the end of arm 24 from the roll 15, whence the spring 21 pulls lever 16 to its normal quiescent position shown in Figure 3.

50 It will be seen from the foregoing that the invention provides a simple and rugged line-space device as embodied in the lever 16 and associated elements, readily adapted for economic manufacture. It will also be seen that lever 16 may 55 be operated to effect line-space rotation of the platen by a somewhat carefree actuation of the lever in a generally downward and rearward direction, and may further serve to release the platen detent by a mere forward swing of the lever 16, the platen detent being restored to operative condition by flipping the lever rearwardly. The cooperation of spring 21 with the lever 16 is such that the operator may accomplish either of these operations without particular regard to the exact manner of manipulating the lever, and in either function, spring 21 restores the lever 16 instantly to its normal quiescent position.

70 While, in this application, there is specifically described one embodiment which the invention may assume in practice, it will be understood that same is shown for the purposes of illustration, and that the invention may be modified, and 75 embodied in various other forms without depart-

ing from its spirit or scope as defined in the appended claims.

What is claimed as new is:

1. In a line-spacing mechanism for typewriters having a rotatable platen and a ratchet wheel 5 rotatable therewith, in combination, a lever mounted for pivotal and endwise movement about the ratchet wheel axis and having a finger-piece at one end, a dog fixed on said lever to cooperate with said ratchet wheel, means for limiting the 10 swing of said lever in line-spacing direction, and spring means acting upon said lever to yieldably resist pivotal and endwise movement thereof with said dog in initial line-spacing position free of said ratchet wheel; whereby actuation of said 15 lever finger-piece moves said dog into coaction with said ratchet wheel to rotate the platen a predetermined extent in line spacing.

2. In a line-spacing mechanism for typewriters, the combination with a rotatable platen, a platen 20 shaft, and a toothed wheel rotatable with said platen, of a lever having an elongate slot bearing on said shaft and forming a fulcrum for said lever permitting endwise and oscillatory movement of said lever, a dog carried on said lever 25 and movable therewith to cooperate with said toothed wheel, means limiting oscillatory movement of said lever to restrict movement of said dog to substantially a tooth pitch, and a tension spring acting upon said lever at a point in line 30 with the longitudinal center of said slot to yieldably resist oscillation of said lever to either side of said line.

3. In a line-spacing mechanism for typewriters having a rotatable platen and a ratchet wheel 35 rotatable therewith, in combination, a lever having a movable fulcrum at the ratchet wheel axis and projecting upwardly therefrom carrying a finger-piece at its upper end, a dog fixed on said lever intermediate the fulcrum and said finger-piece to cooperate with said ratchet wheel, means for limiting the swing of said lever in line-space 40 direction, and a tension spring acting upon said lever to yieldably resist pivotal and endwise movement thereof and yieldably hold said dog in initial line-spacing position free of said ratchet 45 wheel; whereby a downward and rearward pressure on said lever finger-piece tangential to the platen axis against the tension of said spring moves said dog into engagement with said ratchet wheel to rotate said platen a predetermined extent in line spacing.

4. In a line-spacing mechanism for typewriters having a rotatable platen, a shaft therefor and a ratchet wheel rotatable with said platen, in 55 combination, a lever having a finger-piece at one end and having an elongate slot bearing on the platen shaft, forming a fulcrum for said lever permitting pivotal and endwise movement thereof, a dog fixed on said lever to cooperate with 60 said ratchet wheel, a tension spring acting upon said lever to bring one end of the slot thereof against the platen shaft, yieldably resisting pivotal and endwise movement of said lever to hold said dog in initial line-spacing position free of 65 said ratchet wheel, and means for limiting the swing of said lever in line-spacing direction; whereby actuation of said lever finger-piece tangential to the platen axis against the tension of said spring moves said dog into engagement with 70 said ratchet wheel to rotate said platen a predetermined extent in line spacing.

5. In a line-space mechanism for typewriters having a rotatable platen, a ratchet wheel rotatable with said platen and a spring detent cooper- 75

ating with said ratchet wheel, in combination, a line-spacing and detent-release lever pivoted and shiftable at the ratchet wheel axis, a dog carried on said lever which cooperates with said ratchet 5 wheel, means for limiting the swing of said lever in line-spacing direction, and spring means acting upon said lever to yieldably hold said lever in inactive position with said dog in initial line-spacing position, said lever including a part movable therewith into releasing engagement with 10 said spring detent; said lever being movable from inactive position against the force of said spring means, in one direction to rotate the platen in line spacing, and in the opposite direction to release said detent, said spring means acting to restore said lever to inactive position.

6. In a line-space mechanism for typewriters having a rotatable platen, a ratchet wheel rotatable therewith and a spring detent cooperating 20 with said ratchet wheel, in combination, a line-spacing and detent-release lever mounted at the ratchet wheel axis for pivotal and endwise movement, a dog fixed on said lever for cooperation with said ratchet wheel, a stop limiting the 25 swing of said lever in line-spacing direction, and a tension spring acting upon said lever to yieldably hold same in inactive position with said dog in initial line-spacing position free of said ratchet wheel, said lever including a part movable therewith into releasing engagement with 30 said spring detent; said lever upon actuation in one direction from the inactive position, against the force of said spring, being movable to rotate said platen in line spacing, and in a generally opposite direction to release said detent, said tension spring acting to restore said lever to inactive 35 position.

7. In a typewriter, the combination with a rotatable platen, a platen shaft, a ratchet wheel rotatable with said platen and a spring detent 40 cooperating with said ratchet wheel, of a line-spacing and detent-release lever having an elongate slot bearing on said shaft permitting oscillatory and endwise movement of said lever, a dog fixed on said lever for cooperation with said ratchet wheel, a spring acting upon said lever to yieldably hold said lever in ineffective position, said lever including a part swingable into releasing engagement with said detent, means for limiting the oscillatory movement of said lever, said lever being movable in one direction to bring said dog into coaction with said ratchet wheel to 10 rotate said platen in line spacing, and being swingable in a generally opposite direction to bring said lever part into effective position with said detent, said detent-coacting-lever part presenting a recess to admit a portion of said detent 15 to yieldably arrest said lever in detent-releasing position.

8. In a typewriter, the combination with a rotatable platen, a platen shaft, a ratchet wheel rotatable with said platen and a spring detent 20 cooperating with said ratchet wheel, of a line-spacing and detent-release lever having an elongate slot bearing on said shaft and permitting endwise and oscillatory movement of said lever, said lever comprising an upwardly projecting arm 25 terminating in a finger-piece and having a dog fixed thereto for cooperation with said ratchet wheel, said lever also including a downwardly projecting arm terminating in a recess and adapted to move said detent to released position 30 with the detent seating in said recess, a finger extending from said lever and adapted to engage a stop to limit oscillatory movement of said lever, a tension spring yieldably holding said arm in ineffective position; whereby a downward and rearward pressure on said lever arm finger-piece moves said dog into coaction with said ratchet wheel to rotate said platen in line spacing, and a forward pressure on said finger-piece swings said arm into detent-releasing position. 35
